UNITED STATES PATENT OFFICE.

WILLIAM WILLS, OF CANTON, OHIO, ASSIGNOR OF ONE-THIRD TO HOMER E. BLACK AND ONE-THIRD TO WILLIAM L. ROHRER, BOTH OF CANTON, OHIO, AND ONE-EIGHTH TO WM. A. MARSHALL, OF AUSTIN, NEVADA.

INTERNAL-COMBUSTION ENGINE.

1,138,824.

Specification of Letters Patent. Patented May 11, 1915.

Application filed May 21, 1914. Serial No. 839,939.

To all whom it may concern:

Be it known that I, WILLIAM WILLS, a citizen of the United States, formerly a resident of Luning, Nevada, now residing at 5 Canton, in the county of Stark and State of Ohio, have invented a new and useful Internal-Combustion Engine, of which the following is a specification.

My invention relates to internal combustion engines, both of the stationary type and also portable engines such as are used in automobiles, motor boats and the like, and relates more especially to any type of internal combustion engines in which the 15 heavier or non-volatile liquid hydrocarbons are used as fuel. Although the types of engines to which this invention relates are more especially adapted to and designed for the use of the low grade liquid hydrocarbons as fuel, other hydrocarbons of higher tests of efficiency may be utilized if desirable.

My invention further relates to internal combustion engines of this type in which the cylinders of the engines are provided 25 with cooling jackets adapted to contain hydrocarbon oils for the purpose of cooling the cylinders.

This invention relates still further to the internal combustion engines of the class referred to in which a cooling jacket located around the cylinder of the engine is adapted to contain hydrocarbon liquid for the purpose of cooling the cylinder, the heat generated within the explosion chamber causing 35 the hydrocarbon liquid to vaporize, said hydrocarbon vapor being mixed with air supplied to the cooling jacket to form with the hydrocarbon vapor an explosive mixture which is admitted to the cylinder at the 40 proper times and ignited.

One of the objects of my invention is to provide an internal combustion engine in which a relatively heavy or non-volatile hydrocarbon oil may be used for fuel, this 45 oil being heated from the cylinder of the engine, air being passed through said oil for the purpose of carbureting the air, the explosive mixture thus formed being then drawn into the cylinder where it is properly compressed and ignited.

A further object is to provide an internal combustion engine of the class referred to in which the liquid hydrocarbon which is

used for fuel is also passed around the cylinder of the engine for the purpose of cooling 55 the cylinder.

A still further object is to provide means whereby the amount of explosive mixture fed to the cylinder may be varied in accordance with the speed at which it is desired 60 to operate the engine.

A still further object is to provide means for heating the hydrocarbon oil to produce the initial charge or charges of explosive mixture, said heating means being disconnected after the radiation from the combustion chamber of the cylinder has supplied sufficient heat to the liquid hydrocarbon contained in the cooling jacket to vaporize the same. 70

These objects, together with other objects readily apparent to those skilled in the art, I attain by the construction illustrated in the accompanying drawings, although my invention may be embodied in a variety of 75 other mechanical forms, the construction illustrated being chosen by way of example.

In the drawings: Figure 1 is a longitudinal section through a stationary internal combustion engine constructed in accordance 80 with my invention. Fig. 2 is an end elevation of the same, parts being shown in section. Fig. 3 is a detached perspective view upon an enlarged scale of the cap used upon the fuel containing, cooling, jacket showing 85 the air intake pipe and outlet pipe for the explosive mixture. Fig. 4 is a side elevation of an automobile provided with an internal combustion engine constructed in accordance with my invention. Fig. 5 is a side 90 elevation upon a larger scale of an engine such as shown in Fig. 4, parts being shown in section for the purpose of illustration. Fig. 6 is a view similar to Fig. 5 showing the reverse side of the engine. Fig. 7 is a 95 top plan view of the radiator used in the engine shown in Figs. 4, 5 and 6.

Similar numerals of reference indicate corresponding parts throughout the several figures of the drawings. 100

Referring first to Figs. 1, 2 and 3 of the drawings in which a stationary internal combustion engine of the horizontal type is shown, the numeral 1 represents a sub-base upon which the main frame 2 is mounted. 105 Preferably formed integral with the main

frame is the cylinder 3 around which is formed a cooling jacket 4, of the type known as an open jacket, so constructed that liquid contained in the hopper 5 will be allowed 5 to enter the cooling jacket and circulate entirely around the circumference of the explosion chamber 6 of the cylinder. A piston 7 of the usual construction is connected to the crank shaft 8 by means of a connecting rod 9, said crank shaft carrying the usual driving pulley 10. The spark plug 11 is shown entering the explosion chamber 6, said explosion chamber being provided with the usual intake valve 12 and outlet valve 13, the outlet valve, being operated by the usual mechanism shown at 14, which is common in all engines of this type, and controlling the exhaust port 15 to which is connected an exhaust pipe 16. An opening 20 is provided at 17 for the purpose of lubricating the cylinder. So much of the construction is common in all internal combustion engines of the type referred to and no further description of this construction 25 is thought to be necessary as the specific form and detail construction of the several parts going to make up the mechanism hereinbefore described has no further bearing upon the present invention, other than 30 that these parts or their equivalents are necessary in order to form a part of the mechanism to be hereinafter described and claimed.

In engines of this type provided with an 35 open hopper, a collar 18 is usually provided in the upper portion of the hopper. I provide a cap 19 to be clamped down upon this collar by means of a plurality of hooks 20, a gasket 21 being preferably located between the edge of the collar and the cap. Carried by the cap 19 and extending down to a point near the cylinder 3 is an air intake pipe 22 provided near its upper extremity with a valve 23 by which the volume of air passing through said pipe may 40 be increased or diminished as the occasion necessitates. If desired a filling aperture 19^a may be provided in the cap 19, although under ordinary conditions this 45 aperture would not be used. The outlet pipe 24 is also located through the cap 19 and is shown provided with an elbow 25 to which is connected a pipe 26 the opposite end of said pipe being provided with 50 the T 27. A pet cock 28 is located in the T 27 for the purpose of admitting a further supply of air when the mixture becomes too rich. Downwardly extending from the T 55 is a pipe line 29 in which is located a valve 30 through which the quantity of gas delivered to the engine may be throttled, a hand lever 31 being provided for operating the valve. Any suitable form of check valve 32 may also be connected to the pipe line 29 60 if desired, and a suitable back firing screen

33 of any common or well known type is preferably located in said pipe line as close as possible to the engine.

The liquid hydrocarbon to be used as fuel is supplied to the hopper 5 through a pipe 34, which pipe is connected to a small tank 35 provided with suitable means for controlling the supply of oil. The pipe 36 leads from the main source of supply of oil (not shown), and enters the tank 35 preferably through the bottom wall as shown and is provided within the tank with a valve seat 37 adapted to accommodate the float valve 38 which controls the supply of oil admitted to the tank 35 and maintains the oil in said tank and in the hopper 5 at the proper level.

A small container 39 is connected to the hopper 5 by means of a liquid intake pipe 40 and a gas outlet pipe 41. As shown, the liquid intake pipe enters the hopper at a point below the level of the liquid fuel contained in the hopper, thereby insuring a small quantity of liquid within the container 39 at all times. A heater of any common and well known type is located beneath the container 39, preferably an electric heater such as is indicated at 42. Suitable connections are made to a battery 43 or other source of electrical current, and a switch is provided at 44 by which means the heater may be disconnected.

Where heavy oils are used for fuel there will be a sediment left in the bottom of the cooling jacket 4 which must necessarily be frequently removed in order to allow the oil to circulate around the cylinder within said jacket. For this purpose a drain pipe 45 is provided in the cooling jacket at its lowest point, said drain pipe being provided with a valve 46 of any desirable and suitable construction, through which the sediment left within the cooling jacket may be drawn off.

In starting the engine the circuit connecting the battery 43 and heater 42 is closed, the heat radiated in the heater 42 vaporizing a portion of the liquid hydrocarbon within the container 39, the hydrocarbon vapor thus formed passing through the pipe 41 into the hopper 5. Air is drawn through the pipe 22 to the bottom of the hopper 5 and is carbureted as it passes up through the liquid hydrocarbon contained in the hopper. This carbureted air is mixed with the hydrocarbon vapor which passes into the hopper from the container 39 and the explosive mixture thus formed is drawn off through the outlet pipe 25 and through the pipe 26 and pipe line 29 into the explosion chamber 6 of the cylinder where it is ignited at the proper time by the spark plug 11. The exploded charge is carried from the explosion chamber through the exhaust port 15 and pipe 16 in the usual manner.

As the cylinder 3 becomes sufficiently heated from the explosions taking place therein, heat will be radiated from said cylinder through the liquid hydrocarbon contained within the jacket 4 and hopper 5, causing a portion of this liquid hydrocarbon to be vaporized. The heater 42 may then be dispensed with as the carbureted air which passes upward through the oil within the hopper 5 will be mixed with the hydrocarbon vapor formed within the hopper the mixture thus produced being drawn off in the usual manner through the outlet pipe 24 and into the explosion chamber 6 where it is exploded, and the operation of the engine gone on with in the usual manner. As the oil within the hopper 5 is constantly being vaporized, a new supply of oil is being continually admitted to the hopper through the pipe 34 as hereinafter described, the oil circulating around the jacket 4 and keeping the cylinder properly cooled. The cold air drawn in from the outside through the pipe 22 is discharged against the outer face of the cylinder tending to further cool the cylinder.

Figs. 4 to 7 inclusive of the drawings illustrate a slight modification of my invention showing the changes necessary to be made on applying my invention to a portable engine. In this type as well as in the stationary engine a liquid hydrocarbon is utilized both as a cooling agent for the cylinder and as fuel for the engine, the radiation from the cylinder causing the oil to vaporize as in the former case. A supply of oil is carried in a suitable tank such as indicated at 47 from which a supply pipe 48 leads to the cooling jacket 49 of the engine. In cases where the supply tank is placed below the level of the cooling jacket of the engine as is shown in Fig. 4 of the drawings some means is necessary to force the oil from the tank into the cooling jacket and I prefer to use a pump 50, which connects to the tank by means of a tube 51, it being necessary at intervals to pump air into the upper portion of the tank forcing the liquid from the tank through the pipe 48 and into the cooling jacket. Pumps of this character are in general use at present upon automobiles so that it is not thought necessary to further illustrate the construction and operation of the pump shown, as it has no connection with the present invention and is only necessary to maintain the oil in the cooling jacket at the proper level. A shut-off 48^a is provided in the pipe 48 at a point near the engine. The radiator is made in the form of a tank 52 connected to the cooling jacket 49 by means of a pipe 53 which enters the radiator near its base and a second pipe 54 which is connected near the upper portion of the radiator. By this construction the liquid hydrocarbon is allowed to

circulate around the cylinder and through the radiator. An air intake pipe 55 is located in the radiator extending nearly to the bottom thereof and a gas outlet pipe 56 is connected at the upper portion of the radiator, and provided with a valve 57 for adjusting the maximum intake of gas to the cylinders. A T 58 connects the pipe 56 with a downwardly extending pipe 59 and is provided with a pet cock 60, the stem 75 61 of which is elongated and extended through the instrument board 62 and provided upon its extremity with a knob 63. The lower extremity of the pipe 59 is connected to the intake pipe 64 of the carbureter which is of the usual construction and is connected to a carbureter 65 of any desired and well known type. The usual manifold 66 connects the carbureter and explosion chambers of the several cylinders 80 of the engine. A gage 67 is located upon the inner side of the instrument board and is connected near its lower extremity by means of a tube 68 to the cooling jacket 49, and is adapted to show the level of the oil in the 90 radiator tank. The remaining parts of the engine are constructed and operated in the usual manner and no further reference to these parts is considered necessary.

In starting the portable engine just described gasoline is admitted to the carbureter 65 through the supply pipe 69 and air is admitted to the carbureter in the usual manner, mixing with the gasoline vapor and forming an explosive mixture which is carried through the manifold 66 and into the cylinders where it is exploded. As the cylinders become heated the oil circulating through the cooling jacket and radiator tank will be vaporized and will mix with 100 the air drawn in through the pipe 55 and up through the supply of oil in the radiator tank 52, the mixture of gas and air while thus formed being carried through the pipes 56, 59 and 64 and through the carbureter 110 into the manifold from whence it is discharged into the cylinders and exploded. The gasoline supply may then be cut-off by means of the cut-off valve 70 located in the pipe 69 and the engine run upon the heavy 115 oil entirely, said oil circulating through the pipes 53 and 54 and around the cooling jacket for the purpose of cooling the cylinders. A drain pipe 71 is provided in the base of the radiator tank and is provided 120 with a drain valve.

As will be seen from the above description and attached drawings the engines both of the stationary and portable type are constructed very similar to the usual types of 125 such engines and any of the usual types of internal combustion engines may with slight alterations be made to conform with the principles of my invention. In each of the instances illustrated in the drawings it will 130

be observed that the usual water jacket around the cylinder is utilized as a vaporizing chamber for the motive fluid used as fuel for the engine, said motive fluid be also used as a cooling agent to prevent the cylinder from becoming overheated.

In the event that the oil tank, shown at 47 in Fig. 4 of the drawings, is placed above the level of the engine there will be no necessity of providing a pump to raise the level of oil in the cooling jackets and radiator tank, as the oil would naturally seek its own level in the above mentioned jackets and radiator tank. It would be necessary however to provide means for maintaining the oil at a uniform level, in the radiator tank and jacket, similar to the means shown and described upon the stationary engine. It will, of course, be understood that after the gasoline supply has been shut off from the carbureter shown in Fig. 5 of the drawings that although mixture of heavy oil vapor and air is still carried through the carbureter that this is merely done for convenience and that the carbureter serves no other function than to act as a passageway through which the already carbureted mixture is conducted and if desirable a pipe could be provided connecting the manifold directly with the pipe 59 and the result would be precisely the same.

Although the drawings and above specification disclose the best mode in which I have contemplated embodying my invention, I desire to be not limited to the details of such disclosure, for, in the further practical application of my invention, many changes in form and construction may be made, as circumstances require or experience suggests, without departing from the spirit of the invention, within the scope of the appended claims.

I claim:

1. In an internal combustion engine, an oil containing cooling jacket surrounding the cylinder, an oil containing reservoir located upon said cooling jacket and communicating therewith, means for maintaining a uniform level of oil in the reservoir, means for vaporizing a sufficient quantity of oil to start the engine, an air intake pipe extending downward through the top of said reservoir and through the oil contained therein, the lower extremity of said pipe terminating at a point adjacent the explosive chamber and a gas outlet pipe connecting the reservoir and the cylinder.

2. In an internal combustion engine, an oil containing cooling jacket surrounding the cylinder, an oil containing reservoir lo-

cated upon said cooling jacket and communicating therewith, means for vaporizing a sufficient quantity of oil to start the engine, an air intake pipe extending downward through the top of said reservoir and through the oil contained therein, the lower extremity of said pipe terminating at a point adjacent the explosive chamber and a gas outlet pipe connecting the reservoir and the cylinder.

3. In a hydrocarbon motor, an oil containing cooling jacket surrounding the explosion chamber, a vaporizing chamber communicating with the cooling jacket, means for maintaining the oil within the vaporizing chamber at a given level, means for forcing air through the oil contained in the vaporizing chamber and means for feeding the same into the explosion chamber.

4. In a hydrocarbon motor, an oil containing cooling jacket surrounding the explosion chamber, the heat radiated from the explosion chamber being adapted to vaporize the oil contained in the cooling jacket, means for forcing air through the oil contained in the cooling jacket, means for feeding the same into the explosion chamber, and means for operating the engine until the explosion chamber has become sufficiently heated to vaporize the oil contained in the cooling jacket.

5. An internal combustion engine, comprising a jacketed cylinder provided with a hopper, and adapted to contain oil as a cooling agent, an air intake pipe extending into said hopper and discharging against the cylinder, means for maintaining a uniform level of oil in the hopper, means for vaporizing a sufficient quantity of oil to start the engine and a gas feed pipe connecting said hopper to the explosion chamber.

6. In an internal combustion engine, comprising a jacketed cylinder provided with a hopper and adapted to contain oil as a cooling agent, means for maintaining a uniform level of oil in the hopper, means for vaporizing a sufficient quantity of oil to start the engine and a cap detachably secured upon the hopper, said cap provided with an air intake pipe adapted to extend into the hopper and a gas outlet pipe connecting the hopper and the cylinder.

In testimony that I claim the above, I have hereunto subscribed my name in the presence of two witnesses.

WILLIAM WILLS,

Witnesses:

JOHN H. BISHOP,
SYLVIA BORON.
